Primary Examiner — Elizabeth Albert(74) *Attorney, Agent, or Firm* — SNR Denton US LLP; Brian R. McGinley; Anne K. W. Sutton(57) **CLAIM**

The ornamental design for a literature holder, as shown and described.

DESCRIPTION

FIG. 1 is a front elevational view of the literature holder showing the new design;

FIG. 2 is a right side elevational view of the literature holder shown in FIG. 1; the left side view is a mirror image of the right side view;

FIG. 3 is a rear elevational view of the literature holder shown in FIG. 1;

FIG. 4 is a top plan view of the literature holder shown in FIG. 1;

FIG. 5 is a bottom plan view of the literature holder shown in FIG. 1;

FIG. 6 is a front perspective view of the literature holder shown in FIG. 1; and,

FIG. 7 is a rear perspective view of the literature holder shown in FIG. 1.

The broken lines showing the bottom surface and features in FIG. 5 are included for the purpose of showing portions that form no part of the claimed design.
